PARAFFIN SCRAPER

Milam A. Cowen, Gladewater, Tex., assignor of
one-fourth to Edward Rasnek, Kilgore, Tex.

Application October 20, 1937, Serial No. 170,111

2 Claims. (Cl. 166—18)

The invention relates to an oil well tool, and more especially to a scraper device for oil well casings or tubes.

The primary object of the invention is the provision of a device of this character, wherein a plurality of blades of special construction are arranged concentrically about a coupling stem so that said blades will assume a contracted relationship to each other when the stem is being lowered into the well casing or tube and in this manner eliminating any scraping action upon the inner surface of the casing or tube during downward stroke and on the reverse stroke or upward movement of the stem the blades will automatically move to a position for complete scraping action on the inner surface of the casing or tube for the removal of paraffin or other accumulated substance therefrom which creates obstruction to the free flow of oil from the well in the pumping thereof.

Another object of the invention is the provision of a device of this character, wherein the mounting and working of the blades are novel, being self-adjustable for positive scraping operation in the working of the device when introduced into a well casing or tube.

A further object of the invention is the provision of a device of this character, wherein the blades are assisted downwardly in a well casing or tube through the medium of a weight located beneath the said blades in their fitting with carrier or stem therefor and in this downward movement the said blades are inactive for scraping operation.

A still further object of the invention is the provision of a device of this character, which is simple in construction, thoroughly reliable and efficient in operation, strong, durable, automatically adjustable from scraping to non-scraping positions during operation thereof, and inexpensive to manufacture.

With these and other objects in view the invention consists in the features of construction, combination and arrangement of parts as will be hereinafter more fully described, illustrated in the accompanying drawing, which discloses the preferred embodiment of the invention, and pointed out in the claims hereunto appended.

In the accompanying drawing:

Figure 1 is an elevation of the device constructed in accordance with the invention and shown in scraping position within an oil well casing, the latter being in vertical section.

Figure 2 is a side elevation of the device removed from the casing, being partly in section.

Figure 3 is a sectional view taken on the line 3—3 of Figure 4 looking in the direction of the arrows.

Figure 4 is a sectional view on an enlarged scale taken on the line 4—4 of Figure 2.

Figure 5 is a sectional view on the line 5—5 of Figure 2.

Similar reference characters indicate corresponding parts throughout the several views in the drawing.

Referring to the drawing in detail A designates generally a portion of an oil well casing or tube and B the scraping device, respectively, which latter constitutes the present invention and will be hereinafter fully described.

The device B comprises a stem or shank 10 having a major lower portion 11 downwardly tapered and a minor upper portion 12 reversely tapered, while between these portions is a cup-shaped holder forming a carrier 13, being exteriorly formed on the stem or shank 10. This carrier 13 between its side wall 14 which is upwardly flared and the outer surface adjacent thereto of the stem or shank 10 forms an annular downwardly directed wedge-shape seat 15 for a plurality of sector or segment shaped scraper blades 16, these being downwardly tapered in a longitudinal direction or reversely to the minor portion 12 of the stem or shank 10. The blades 16 at their narrower ends are adapted for seating and wedge engagement in the seat 15 which is the scraping position for said blades on the upward stroke or movement of the stem or shank 10.

Concentrically about the minor portion 12 and extending from within the carrier 13 to a spacing spider or ring 17 and following the taper of said portion 12 is a series of uniformly spaced guide rods 18 which are passed through suitable clearances or passages therefor provided in said blades 16 and in this manner the latter are guided toward and away from the said carrier 13 in the operation of the device.

The spider or ring 17 is releasably held in place on a reduced exteriorly threaded upper end 19 on the stem or shank 10 by a nut 20 engaged with said end 19, the latter being adapted for coupling with a tool line or a sucker rod (not shown). The rods 18 are removably engaged with the spider or ring 17 when the same is detached from the end 19 of the stem or shank 10, and in this manner the blades 16 can be pulled off of the said rods 18, the latter being welded or otherwise secured to the carrier 13 interiorly thereof.

The lower end 21 of the stem or shank 10 is

exteriorly threaded for fastening to a coupling box (not shown) of the line or sucker rod and this box together with the lower major portion 11 of the stem or shank effects weight below the blades 16 to assist in the lowering of the device in the well casing or tube A.

Between the blades 16 in the mounting thereof on the rods 18 for sliding movement are gaps or spaces 22 which allow the said blades to approach each other for adjustment thereof to different cross-sectional sizes or diameters of tubes or casings. When the said blades are in scraping position they will have close contact with the inner surface of the casing or tube A and such blades at their larger ends are of greater circular diameter than the open end of the carrier 13. When the blades 16 move away from the carrier 13 on the down stroke of the stem or shank 18 they will not scrape the inner surface of the casing or tube A, the device being lowered into the latter and during this movement the blades are in nonscraping position, while on the upstroke

of the device the said blades 16 move to scraping position.

The upstroke of the device removes paraffin or the like 24 from the inner surface of the casing or tube A for the free flow of oil from the well 5 during the pumping operation.

What is claimed is:—

1. A device of the character described, comprising a stem having an upwardly tapered minor portion, a cup-shaped carrier located at the 10 tapered minor portion, and shiftable sector shaped blades about the said minor portion and reversely tapered thereto for seating and unseating in and from the carrier.

2. A device of the character described, comprising a stem having a tapered portion, a plurality of sector shaped scraper blades around said tapered portion, a cup shaped receiver for the blades, and means for guiding the blades into and from the receiver. 15 20
